UNITED STATES PATENT OFFICE.

LAURENT A. FROBERGER, OF LYNN, MASSACHUSETTS, ASSIGNEE TO GENERAL ELECTRIC COMPANY, A CORPORATION OF NEW YORK.

CONTROLLER FINGER

Application filed October 7, 1921. Serial No. 505,971.

To all whom it may concern:

Be it known that I, LAURENT A. FROBERGER, a citizen of the United States, residing at Lynn, in the county of Essex, State of Massachusetts, have invented certain new and useful Improvements in Controller Fingers, of which the following is a specification.

My invention relates to contact fingers for electric circuit controllers and has for its object the provision of an improved device of this character which will be of a rugged construction and at the same time simple and cheap to manufacture. Devices of this character, commonly known as controller fingers, are liable to be subjected to hard usage and the construction must, therefore, be of the most rugged character. As often constructed a contact button of copper is riveted at its center to a contact spring. This construction does not, however, prevent the button from getting loose and turning on its riveted center. One of the objects of my invention is to produce an arrangement in which such turning will be prevented even though the button should become loose, and which is constructed of punchings which may be easily assembled.

30 Other objects and purposes of my invention will appear in the course of the following description in which I have disclosed my invention in one form for purposes of illustration.

In the accompanying drawings illustrating my invention, Fig. 1 is a perspective view of an assembled controller finger embodying my invention; and Fig. 2 is a perspective view of the separated parts.

Referring to the drawing, 10 indicates the contact button which is the part that actually makes contact with the segment on the controller. This button is made of hot pressed copper provided with ears 11. 12 represents an elongated spring member preferably made of phosphor-bronze. This member is notched on opposite sides of one end at 13 and is provided with holes 14 for securing it to a suitable support. 15 represents a copper shunt made of two or more different pieces of sheet copper. This shunt is the same shape as the spring strip 12, being provided with similar notches 16 which coincide with the notches 13 on the spring strip when the two parts are superimposed. 17 The shunt in its flat condition is slightly

longer than the spring strip 12 in order to provide for the usual loop 17 to permit a slight extension under bending. Slotted holes 18 are provided to coincide with the holes 14 for the supporting screws. A washer 19, likewise notched at 20, to correspond to the notches 13 and 16, is provided to be superimposed upon the copper shunt. This washer is preferably of spring tempered sheet steel. 65

Fig. 1 shows the parts assembled. The spring strip 12 is placed on the contact button so that the notches 13 coincide with the ears 11, the button being slightly less in width than the strip. The copper shunt is superimposed upon the spring strip with its notches likewise corresponding with the ears 11, the shunt being the same width as that of the spring. The washer 19 is then superimposed upon the copper shunt with its notches coinciding with the notches on the shunt. The ears 11 are then bent over the washer and pressed down hard onto the washer as shown in Fig. 1. Since the ears 11 enter the notches in the three parts, the button is positively prevented from turning, even though the button should become slightly loosened. A very firm contact having a liberal contact area is likewise made between the button and the other parts. The assembling of the parts of the contact finger is a very simple operation with no opportunity of displacement. The sheet metal parts may all be punchings and hence may be produced with exact uniformity at a low cost. The parts when assembled are practically a unit.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention the scope of which is set forth in the annexed claims. 100

What I claim as new and desire to secure by Letters Patent of the United States, is:—

1. A controller finger comprising an elongated spring member having a notched end and a contact button provided with ears which enter the notches and are bent over the spring and pressed down so as to firmly grip the spring member between the bent 105 110 115 120 125 130 135 140 145 150 155 160 165 170 175 180

over portion of the ears and the main body of the button.

2. A controller finger comprising an elongated spring member having one end provided with oppositely disposed notches and a contact button provided with ears which enter the notches and are bent over and pressed down so as to firmly grip the spring member between the bent over portion of the ears and the main body of the button.

3. A controller finger comprising an elongated spring member having one end provided with oppositely disposed notches and a contact button provided with integral ears which enter the notches and are bent over and pressed down so as to firmly grip the spring member between the bent over portion of the ears and the main body of the button.

20 4. A controller finger comprising an elongated spring member having a notched end, a similarly shaped and notched copper shunt

superimposed thereon and a contact button provided with ears which enter the notches in the two parts and are bent over and 25 pressed down so as to firmly grip the said parts between the bent over portion of the ears and the main body of the button.

5. A controller finger comprising an elongated spring member provided at one end 30 with oppositely disposed notches, a similar shaped notched copper shunt superimposed thereon, a similarly notched metallic washer superimposed on said shunt and a contact button provided with integral ears which 35 enter the notches in said parts and are bent over and pressed down onto the washer so as to firmly grip the parts between the bent over portion of the ears and the main body of the button.

In witness whereof, I have hereunto set my hand this 4th day of October, 1921.

LAURENT A. FROBERGER.
